CLAIM

The ornamental design for a particle size and wetness reducing device, as shown and described.

DESCRIPTION

FIG. 1 is a front and top perspective view of a particle size and wetness reducing device.

FIG. 2 is a front side elevational view of the particle size and wetness reducing device.

FIG. 3 is a left side elevational view of the particle size and wetness reducing device.

FIG. 4 is a rear side elevational view of the particle size and wetness reducing device.

FIG. 5 is a right side elevational view of the particle size and wetness reducing device.

FIG. 6 is a top plan view of the particle size and wetness reducing device.

FIG. 7 is a bottom plan view of the particle size and wetness reducing device.

FIG. 8 is a front and right side perspective view of the particle size and wetness reducing device.

FIG. 9 is an exploded front and right side view of the particle size and wetness reducing device comprising the exterior tube and the interior redirectors component.

FIG. 10 is a front side elevational view of the exterior tube component of the particle size and wetness reducing device.

FIG. 11 is a left side elevational view of the exterior tube component of the particle size and wetness reducing device.

FIG. 12 is a rear side elevational view of the exterior tube component of the particle size and wetness reducing device.

FIG. 13 is a right side elevational view of the exterior tube component of the particle size and wetness reducing device.

FIG. 14 is a top plan view of the exterior tube component of the particle size and wetness reducing device.

(Continued)

FIG. 15 is a bottom plan view of the exterior tube component of the particle size and wetness reducing device.
 FIG. 16 is a front view of the interior redirectors component of the particle size and wetness reducing device.
 FIG. 17 is a right side elevation view of the interior redirectors component of the particle size and wetness reducing device.
 FIG. 18 is a rear view of the interior redirectors component of the particle size and wetness reducing device.
 FIG. 19 is a left side elevation view of the interior redirectors component of the particle size and wetness reducing device.
 FIG. 20 is a top plan view of the interior redirectors component of the particle size and wetness reducing device; and,
 FIG. 21 is a bottom plan view of the interior redirectors component of the particle size and wetness reducing device.
